ATTORNEY

UNITED STATES PATENT OFFICE.

WALTER A. REED, OF MOUNT UNION, PENNSYLVANIA.

FIRST-AID OUTFIT.

Application filed October 30, 1920. Serial No. 420,770.

To all whom it may concern:

Be it known that I, WALTER A. REED, a citizen of the United States, residing at Mount Union, in the county of Huntingdon and State of Pennsylvania, have invented new and useful Improvements in First-Aid Outfits, of which the following is a specification.

This invention relates to first aid outfits, and embodies amongst other features a receptacle of a size to be conveniently carried about the person, and in which are compactly arranged the various articles essential in first aid treatment.

15 In carrying out the invention, I provide a receptacle adapted to contain bandages and the like, the receptacle also including a removable tray upon which are arranged bottles, and instruments found necessary in first aid treatment, means for providing the bottles and instruments in fixed relation to the tray, and permitting a ready separation of any of the elements from the tray when use is desired.

20 25 The nature and advantages of the invention will be better understood when the following detail description is read in connection with the accompanying drawing the invention residing in the combination, construction and arrangement of parts as claimed.

In the drawing forming part of this application like numerals of reference indicate the similar parts in the several views and where-

30 35 in:

Figure 1 is a view of the outfit complete.

Figure 2 is a sectional view taken on line 2-2 of Figure 1.

Figure 3 is a view of the tray removed from the receptacle.

Figure 4 is a view of one of the thumb covers.

Referring to the drawing in detail 10 indicates a receptacle and 11 the cover therefor.

40 45 The receptacle being constructed of any suitable material and of a size to be conveniently carried in the pocket of the user. Removably positioned within the receptacle is a tray 12 constructed to support the plurality of

bottles containing medicines, and implements necessary to first aid treatment. Arranged within the receptacle 10 beneath the tray is a roll of bandage 13 and a plurality of covers 14 to fit the thumb or finger such as shown in Figure 4. Each cover is provided with securing elements adapted to surround the wrist of the wearer.

The tray 12 has established thereto an elastic tape 15, this tape and its terminals are stitched to the tray adjacent the closed sides thereof, and also stitched at suitable points in its length to provide a plurality of loops 16 extended transversely across the tray. Each of these loops receives and supports upon the tray a bottle 18, there being preferably four of these bottles, and one containing peroxide of hydrogen for washing out cuts and bruises. One containing iodine to apply after the use of the peroxide, one containing an eye-wash and one containing sweet oil for application to burns. Secured to the tray 12 at one side of its transverse center is a loop 20 to receive and support upon the tray a pair of tweezers 21 utilized for removing splinters or the like from the hand, while arranged at the opposite side of the transverse center of the tray is a loop 22 for supporting a syringe 23. Extending longitudinally of the tray 12 is an elastic loop 24 which is arranged adjacent one end of the tray and receives and supports a mirror 25. Carried by the tray centrally thereof is a handle 26 by means of which the tray cover can be conveniently inserted within or removed from the receptacle. A complete outfit also embodies a book of instructions which is arranged upon the tray.

While it is believed that from the foregoing description the nature and advantages of the invention will be readily apparent, I desire to have it understood that I do not limit myself to what is herein shown and described, and that such changes may be resorted to when desired as fall within the scope of what is claimed.

90 95 What I claim is:

A device of the class described comprising a receptacle, a cover therefor, a tray remov-

2
ably positioned within the receptacle, a handle secured to the bottom of said tray intermediate the ends thereof, a pair of longitudinally extending relatively short loops secured to said tray upon opposite sides of said handle, a longitudinally extending relatively long elastic loop secured to said tray

and spaced from one of the short loops, and a relatively long transversely disposed elastic loop secured to said tray and spaced from 10 the other short loop.

In testimony whereof I affix my signature.

WALTER A. REED.
